F. A. ZIKA.

CURRENT CONDUCTING AND DISTRIBUTING DEVICE FOR INTERNAL COMBUSTION ENGINES.
APPLICATION FILED JUNE 9, 1913.

1,105,741.

Patented Aug. 4, 1914.

UNITED STATES PATENT OFFICE.

FRANK A. ZIKA, OF CHICAGO, ILLINOIS, ASSIGNOR OF ONE-HALF TO JAMES E. BARRY,
OF CHICAGO, ILLINOIS.

CURRENT CONDUCTING AND DISTRIBUTING DEVICE FOR INTERNAL-COMBUSTION ENGINES.

1,105,741.

Specification of Letters Patent.

Patented Aug. 4, 1914.

Application filed June 9, 1913. Serial No. 772,587.

To all whom it may concern:

Be it known that I, FRANK A. ZIKA, a subject of Austria-Hungary, and resident of Chicago, in the county of Cook and State 5 of Illinois, have invented certain new and useful Improvements in Current Conducting and Distributing Devices for Internal-Combustion Engines, of which the following is a full, clear, and exact specification.

10 My invention relates to current conducting and distributing devices for internal combustion engines.

Heretofore the common, and I may say universal practice has been to separately 15 connect the spark plugs of such engines with the current distributers by numerous wires, corresponding in size with the slight current to be carried by them, and which are therefore so small that they are frequently 20 broken by the constant vibration produced by the operation of the engine, which effect finally crystallizes the copper of their structure thereby increasing their tendency to break. The rubber covering of the wires is 25 deleteriously effected by corrosion from exposure to oil, and loss of insulation causing short circuiting by water, which wires being as they are, more or less over burdened with a heavy coating of insulation, frequently 30 break, or are short circuited by water without there being any visible exterior signs to indicate where the trouble is, whether a short circuit or a break, and if a break where it is located, and as a result of which this numerous 35 wire connection is entirely unreliable and unsatisfactory.

The prime object of this invention is the production of a means by which it is for the first time made possible and practical to connect the spark plugs of internal combustion engines with the distributer, however many there may be, and in the entire absence of the use of numerous, delicate wires, and of any wire which can possibly be subject to 40 any of the conditions and objections above specified. Furthermore to accomplish the above object by means of a fixed structure hereinafter specifically described as such, as distinguished from a rotatable structure described in another application filed concurrently herewith.

Another object of my invention is to provide a substantially and relatively non-rotatable, but oscillatable current-conducting

means upon the cylinder head of an internal 55 combustion engine in proper relation with its spark plugs thereof, (there being a separate conductor for each spark plug) and to electrically energize, or charge said conductors in sequential order by means adapted to 60 be moved in proper unison and relation with the respective reciprocating pistons of said engine. Furthermore to provide means for changing the coincident relation of the energizing means with the respective movements 65 of said pistons by oscillating said conductors, thereby to advance and retard the time of producing the ignition sparks within the cylinders of said engine.

Other and further objects of my invention 70 will become readily apparent to persons skilled in the art from a consideration of the following description when taken in conjunction with the drawings, wherein:—

Figure 1 is an elevation of a portion of an 75 automobile, showing an engine mounted thereto as means for propelling the vehicle and showing my device located upon the engine and adapted to be operated therewith. Fig. 2 is the central section taken on line 80 2—2 of Fig. 1. Fig. 3 is an enlarged section taken on line 3—3 of Fig. 1. Fig. 4 is an end view of the device. Fig. 5 is a section taken on line 5—5 of Fig. 3.

In all the views the same reference characters are employed to indicate similar parts.

In a co-pending application, executed and filed of even date herewith, I have shown a similar device to the one disclosed in this application with the exception that in the before mentioned application the conducting and distributing structure is bodily rotatable and a single conductor is employed to distribute the spark current to the respective spark plugs of the engine, while in the present application there are a plurality of relatively stationary conductors, one for each spark plug, and a separate rotating device employed for distributing the current to the respective conductors in order that the spark plugs may be properly supplied with sufficient current-energy to produce the ignition sparks.

In the particular embodiment herein disclosed 10 is a side frame of an automobile; 105 11 is an internal combustion engine; 11' is the head of the engine; 12 is the magneto-electric machine for producing high poten-

tial current; 13 is a radiator for cooling the water of the engine; 14 is the hood covering the engine and parts; 15 is a fly wheel of the engine; 16 is the steering tube for supporting the steering wheel that is connected to the running gear of the vehicle, 17, 18, 19 and 20 are the spark plugs for the respective cylinders of the engine. So far as described the parts named are generally common in automobile structures.

21 is my improved current conductor and distributing element. The body part may be composed of a single piece of hard rubber, as shown, or of any other suitable material having the qualities and capability of insulating high potential currents. It may, or may not, be surrounded with a metallic protecting jacket, such as shown in my co-pending application. In the present specific structure the protecting jacket is omitted and a solid rod or cylinder of hard rubber, or of gutta percha is shown. It is supported at its respective ends by means of brackets 22 and 23, each comprising an adjustable strap 24 secured to the cleats 25, and to the head of the engine. The strap 24 is secured to the cleats 25 by means of screws 26. The straps 24 are not so tight as to prevent slight rotation or oscillation, of the member 21 when required.

Secured to the right hand end of the member 21, is a metal cap 27, to provide a housing or casing for the current distributing device. Conductors 28, 29, 30 and 31 are embedded in the rubber body portion 21' of the distributing member and terminate in a single longitudinal and radial plane in eyes or terminals 32, 33, 34, 35, respectively. These terminals are connected to the spark plugs by means of a telescopic, elongatable conductor consisting of the rod 37 secured to the plug by a clip 30 to which it is pivoted, and which is held in place by a cap screw 39. Freely movable over and in contact with the rod 37 is a tube 40, terminating in a pivotal end 41 which is connected to the eye 35, so that when the member 21 is slightly rotated, or oscillated, the distance between the eye and the respective spark plug is thereby changed, the telescopic relation of the parts described being adapted to compensate for such changed distance. To thoroughly insulate this connection I prefer to cover it with a hard rubber jacket 42. Each of the conductors, connecting the respective spark plugs and high potential terminals, are made in the manner described.

Each of the embedded conductors in the member 21, terminates at the right hand end in substantially flush relation for co-operative operation with the distributing and rotating conducting arm 43. This arm 43, is held firmly on a gear wheel 44, as by an insulating block, or plate, 45. The gear wheel 44 has ball bearing supports on the magneto 12

as by ball bearings 46. The gear wheel 44 is rotated by means of the spur gear 47 which is secured to the armature shaft of the magneto and which in turn is rotated through the instrumentality of a pair of bevel gears 48 and 49 by the shaft 50, said gears being connected by any suitable means, with the valve shaft, or with the main shaft, of the engine, and the geared relation is such that the distributor 43 shall rotate in proper unison with the reciprocation of the respective pistons.

The rotating distributor 43 terminates, as at 51, for electric contact relation with the bell crank arm 52 that is pivoted to a shaft 53 that extends on the outside of the magneto 12, for connection with a crank arm 54.

An electric conductor 55 passes through the center of the member 21 and terminates at the left hand end in an enlarged end and at the other end is in electrical association with the rotatable distributor 43.

An electric conducting wire 57 connects the bell crank arm 52 with the high potential circuit of the magneto, so that when the bell crank arm 52 is moved into the position shown in Fig. 1, whereby the end thereof makes contact with the end 51 of the distributor 43, the current from the magneto is distributed through the conductors, 28, 29, 30 and 31, and is imparted to the one over which the distributor 43 may at the time be, and thereby the distributor directs the current into the said conductors in their regular consecutive order in unison with the vibration of the respective pistons.

Connected to the crank arm 54 is the link 58, preferably of hard rubber, or the like, which is pivotally connected, as at 59, to a reciprocatable rod 60, said rod finding bearings in the brackets 61, 62 and 63. When the rod 60 is moved in direction toward the magneto the arm 52 will be brought into contact with the end of the distributor 51 and when the rod is moved in the opposite direction contact will be broken between the bell crank arm 52 and the end 51 of the distributor.

A battery B is adapted for producing sparks suitable for the spark plugs through the instrumentality of the spark coil which may be located in the box or casing 64, the general operation and arrangement of which is clearly described and shown in detail in my co-pending application to which reference has heretofore been made. A handle 65 on the box 64 operates the reciprocatable rod 60 by the instrumentality of a, preferably, insulating link 66 which is connected between the handle 65 and the rod 60, so that when the handle 65 is moved in direction toward the magneto the connection will be made between the magneto and the distributing device, and when the handle 65 is moved in the opposite direction said connection will be broken and connection will be estab- 120 125 130

lished between the central conductor 35, and the distributor 43, and the respective conductors, in the distributing member 21, and the said conductors will then be energized by the battery B through the instrumentality of the spark coil heretofore described.

When the handle 65, of the box 64, is moved to the left, the reciprocatable conductor 68 is withdrawn and no longer makes contact with the terminal 56 of the central conductor 53, and therefore circuit between the secondary winding of the spark coil is thereby broken, and when the rod 60 is moved to the right, coincidently the circuit from the magneto to the said conductors, in the member 21 is effected, so that either of the two sources of electric energy may be employed for producing the necessary current to vitalize the spark plugs.

10 The member 21 is slightly rotatable, or oscillatable, for the purpose of changing the lead, of the spark-time, so that the contacts afforded by the projecting ends of the respective conductors in the casing 27 occupy different circumferential positions, thereby to retard or advance the time that the spark is to be made in the respective cylinders with reference to the reciprocations of the pistons. To this end I provide a projecting 15 arm 70 pivotally connected to a link 71, as at 72, and to an arm 73 that is pivoted in the bracket 62 as by the shaft 74. On the other end of the shaft 74 is a similar arm 75 connected by ball and socket support to a link 30 76 that is similarly connected to an arm 77 which is responsive to the spark retarding lever carried on the steering wheel of the vehicle, so that when the spark retarding lever is moved, in the manner usual with such devices, the distributing member 21 is thereby oscillated for changing the spark-time relation of the pistons.

Other specific means than those shown may be employed for carrying my invention 45 into effect without departing from the spirit and within the scope of the appended claims. As an illustration of this statement the high potential magneto may be short-circuited instead of having its circuit open, when it is 50 desired to throw it out of operation, and other means than shown may be employed for connecting the secondary circuit of the induction coil with the respective distributing conductors for the purpose intended.

55 Having described my invention what I claim and desire to secure by Letters Patent of the United States is:

1. A device for the purposes described comprising in combination an engine having 60 a plurality of cylinders and corresponding spark plugs, a relatively fixed conductor supporting member thereon, a plurality of conductors confined therein, terminating at one end thereof, having their inner ends 65 connected to the spark plugs, respectively;

a current distributor for coöperation with the outer ends of said conductors and means for relatively oscillating said distributor and conductor terminals to change the spark time.

2. A device of the character described comprising a longitudinally extending current conductor supporting member; a plurality of conductors therein terminating at one end thereof; the other ends thereof spaced apart and projecting radially from said supporting member, adapted for connection to the respective spark plugs, of an engine; rotatable means, for consecutive electrical association with said end terminals; means for rotating said rotatable means, and means for electrically energizing said rotatable means.

3. A device of the character described, comprising a longitudinally extending current conductor supporting member, adapted to be oscillated upon its support; a plurality of conductors therein terminating at one end thereof; the other end of said conductors spaced apart and projecting laterally from said supporting member, adapted for connection to the spark plugs respectively of an engine; rotatable means for consecutive electrical association with said end terminals; means for rotating said rotatable means; means for oscillating said member, and means for electrically energizing said rotatable means.

4. A device of the character described, comprising a longitudinally extending current conductor supporting member adapted to be oscillated upon its support; a plurality of conductors therein terminating at one end thereof; the other ends thereof spaced apart and projecting laterally from said supporting member, adapted for connection to the respective spark plugs of an engine; rotatable means for consecutive electrical association with said end terminals; means for rotating said rotatable means; means for oscillating said supporting member; two sources of electric current for energizing said rotatable member and a switch controlling said sources of electric current to connect either current source to said rotatable member.

5. A device of the character described comprising a relatively long, oscillatable member; means for supporting said member, to permit rotative oscillation thereof; a plurality of current conductors extending through said member and terminating at intervals; laterally projecting terminals connected to the inner ends of said conductors, respectively, each adapted for connection to a spark plug; means to consecutively energize said conductors to be moved in time relation therewith and with the power shaft of an engine with which the device is to be associated and means to relatively oscillate

said member to vary said time relation with reference to said conductors.

6. A device of the character described comprising a relatively long oscillatable member; means for supporting said member to permit rotative oscillation thereof; a plurality of conductors extending partly through said member and terminating at intervals; laterally projecting terminals, connected to the inner ends of said conductors, respectively, properly spaced apart, to adapt them for connection to spark plugs; rotatable means to consecutively energize said

conductors adapted to be moved in time relation with the power shaft of an engine with 15 which the device is to be associated and means to rotatively oscillate said member with relation to said energizing means.

In witness whereof, I have hereunto set my hand and affixed my seal, this 7th day 20 of June, A. D. 1913.

FRANK A. ZIKA. [L.S.]

Witnesses:

JNO. G. ELLIOTT,
MILDRED ELSNER.
